Samuel G. Bent

United States Patent Office.

SAMUEL S. BENT, OF PORT CHESTER, NEW YORK.

Design No. 2,817, dated October 29, 1867.

DESIGN FOR A NAME-PLATE.

The Schedule referred to in these Letters Patent and making part of the same.

TO ALL WHOM IT MAY CONCERN:

Be it known that I, SAMUEL S. BENT, of the city and State of New York, have invented or produced a new and original Design for a Name-Plate; and I do hereby declare the following to be a full, clear, and exact description of the said design, reference being had to the annexed drawing, making part of this specification, wherein—

Figure 1 is a photographic view of said design, and

Figure 2 is a section vertically through the name-plate.

The name-plate design is adapted to parties making iron work for stable fittings, saddlers, and other parties in this line. The said design consists in a figure of a saddled horse in relief as shown. Surrounding the horse is a ring forming the name-plate, with a loop at its upper end, so that it may be hung upon a nail. Below the ring is a receptacle, of the shape shown, and imitation straps suspend the same from the ring. Upon the surface of this receptacle is the design of a dog in relief as shown.

What I claim, and desire to secure by Letters Patent, is—

The ornamental design of the name-plate, and the accompanying configurations, as shown.

In witness whereof I have hereunto set my signature this 9th day of August, 1867.

Witnesses:

CHAS. H. SMITH,

GEO. D. WALKER.

SAMUEL S. BENT.
